(57) **CLAIM**

The ornamental design for an otoscope, as shown and described.

DESCRIPTION

FIG. 1 is a perspective view of an otoscope in accordance with the new design;

FIG. 2 is a front view of the otoscope of FIG. 1;

FIG. 3 is a rear view of the otoscope of FIG. 1;

FIG. 4 is a left side view of the otoscope of FIG. 1;

FIG. 5 is a right side view of the otoscope of FIG. 1;

FIG. 6 is a top plan view of the otoscope of FIG. 1; and,

FIG. 7 is a bottom plan view of the otoscope of FIG. 1.

The broken lines in the figures are directed to portions of the otoscope that form no part of the claimed design.
